UNITED STATES PATENT OFFICE.

WILLIAM W. WAINWRIGHT, OF CONNERSVILLE, INDIANA, ASSIGNOR TO
THE P. H. & F. M. ROOTS COMPANY, OF SAME PLACE.

DESIGN FOR A HEAD FOR ROTARY PUMPS.

SPECIFICATION forming part of Design No. 25,444, dated April 28, 1896.

Application filed March 23, 1896. Serial No. 584,550. Term of patent 14 years.

To all whom it may concern:

Be it known that I, WILLIAM W. WAINWRIGHT, a citizen of the United States, residing at Connersville, Fayette county, Indiana,
5 have invented and produced a new and original Design for Heads for Rotary Pumps, of which the following is a specification, reference being had to the accompanying drawing, showing the same in perspective.

o The leading feature of my design consists in a plate from one surface of which projects a pair of parallel interrupted bosses, braces projecting from the face of the plate and joining the exterior of the bosses.

In the drawing, A is the plate, and B B are 15 the bosses projecting parallel with each other from one face of the plate. The inner portions C of these bosses are separated from the outer portions by the interrupting spaces D. Braces E project from the face of the plate 20 and join the exterior of the bosses.

What I claim is—

The design for a head for a rotary pump, substantially as shown and described.

WILLIAM W. WAINWRIGHT.
